UNITED STATES PATENT OFFICE.

JAY HIRAM CUMMINGS, OF ELMIRA, NEW YORK.

AUTOMATIC ROUGH-GRINDING MECHANISM FOR PISTON-RINGS

1,393,668.

Specification of Letters Patent.

Patented Oct. 11, 1921.

Application filed December 16, 1920. Serial No. 431,215.

To all whom it may concern:

Be it known that I, JAY HIRAM CUMMINGS, a citizen of the United States of

America, residing at Elmira, in the county 5 of Chemung and State of New York, have invented certain new and useful Improvements in Automatic Rough-Grinding Mechanism for Piston-Rings, of which the following is a specification.

10 The primary object of the invention is the provision of a compact and serviceable device for rough grinding piston rings and the like, automatic feeding and holding means being provided for the work during 15 the grinding operation.

A further object of the invention is the provision of an automatic chuck and feed device for piston rings serviceable in connection with the rough grinding of rings, the 20 device possessing great strength and durability.

A still further object of the invention is the provision of an automatic feed and chuck for piston rings whereby the rings are successively presented and held for grinding on the opposite faces thereof by means of a double disk grinder, the mechanism being simple in construction and economical in manufacture.

30 With these general objects in view, the invention consists of the novel form, combination and arrangement of parts hereinafter more fully described in connection with the accompanying drawings, and in which like 35 reference characters indicate corresponding parts throughout the several views.

In the drawings,

Figure 1 is a side elevational view of the automatic chuck and feed mechanism,

40 Fig. 2 is an end elevational view thereof showing the device in connection with a double disk grinder during the grinding operation,

Fig. 3 is a top plan view thereof including the showing of the double disk grinder with the disk guide,

Fig. 4 is a vertical central sectional view through the clutch longitudinally of the machine,

50 Fig. 5 is an elevational view of a portion of the chuck showing a piston ring held in position by the adjustable jaw of the chuck,

Fig. 6 is a perspective view of the chuck plate detached,

55 Fig. 7 is a perspective view of one of the chuck jaws detached, and

Fig. 8 is a perspective view of one of the piston rings upon which the machine is adapted to operate.

Referring more in detail to the drawings, 60 my invention broadly consists of a magazine 10 for supplying rough piston rings such as 11 to the holding mechanism of a clutch plate 12 for the purpose of grinding the opposite faces or sides of the ring 11 by 65 means of a double disk grinder 13. The grinder 13 consists of parallel emery wheels mounted upon an operating shaft 14 with a guiding disk 15 for the chuck plate 12 positioned between the separated emery wheels 70 designated 13'.

The feed magazine 10 is of tubular formation, comprising sections 16 and 17, semi-circular in cross section and connected together by hinges 18 at one side of the magazine 75 and normally maintained closed by a suitable latch 19 at the opposite side of the magazine. A piston or flange 20 is mounted for movement within the bore of the magazine 10 for feeding the piston rings 80 contained therein toward the opposite or discharge end thereof. Any suitable means for moving the piston 20 toward the discharge end of the magazine 10 may be employed, and it is deemed unnecessary to illustrate 85 the same herein.

A stationary bracket 21 mounted upon a fixed horizontal shaft 22 has a head or stop 23 at its free end positioned opposite the discharge end 24 of the magazine 10 for 90 abutting engagement by a ring when ejected from the magazine 10 by the piston 20. The chuck plate 12 is journaled for rotation upon the shaft 22 by a hub consisting of opposite sections 25 and 26 secured together 95 by screws 27 and having a central chamber 28 within the hub. Opposite extensions 25' and 26' of the hub sections 25 and 26 respectively are journaled upon the shaft 22 for convenience in rotating the chuck upon the 100 said shaft during the operation of the device.

A plurality of ring receiving openings 29 are provided in the plate 12, each of said openings having a chuck jaw 30 slidable in a radial extension 31 of the opening. 105 Hereby a piston ring 11 is clutched in the opening 29 by means of the jaw 30 when the jaw is released in the manner hereinafter described. Each jaw 30 has an inwardly extending rod 32 passing through a rectangular opening 33 in the plate 12 with anti-friction rollers 34 upon the inner free end of

the rod 32 within the chamber 28 inwardly of the inner edge 35 of the plate 12. A spring 36 surrounds the rod 32 within the opening 33 and bears upon the inner side of the opening 33 and against a shoulder 37 carried by the rod 32 and whereby the clutch jaw 30 is normally positioned outwardly for holding the piston ring as best illustrated in Fig. 5 of the drawings.

10 A double cam 38 secured upon the shaft 22 has a groove 39 in the inner face of each portion of the cam adapted for the reception of the wheels 34 with the rod 32 in the space 40 between the sides of the cam 38 when the 15 chuck is revolved upon the shaft 22 around the cam. The operation of the invention will be apparent from this detail description thereof, the ring 11 ejected from the end 24 of the magazine 10 passing into and projecting through one of the openings 29 of the plate 12 when such opening comes in alignment with the bore of the magazine 10 during the revolution of the chuck.

At such times, the head 23 acts as a stop 25 for the ring and a further rotation of the chuck plate 12 substantially 5° brings the rollers 34 of the chuck jaw 30 outwardly of the exit 41 of the cam 38 permitting the spring 36 to cause the jaw 30 to snap closed 30 upon the ring 11 whereby the ring is held in the opening 29 during the travel of the plate 12 in the direction indicated by the arrow in Fig. 2 of the drawings. The turning of the head 26 is preferably timed 35 for stopping the plate 12 when the openings 29 pass each quarter positioned so that each opening 29 will be positioned for an instant successively in alignment with the bore of the magazine 10 and between the sides 13' 40 of the double disk grinder 13. The grinder operates in this manner upon the sides of the ring 11 and the continued turning of the chuck plate 12 substantially 45° from the point of grinding, brings the rollers 34 of 45 the chuck jaw within the entrance end 42 of the cam 38 so that the cam grooves 39 cause the spring 36 to be compressed and the jaw 30 released from the ring 11 when the opening 29 is at substantially the bottom of 50 the plate 12. The ring 11 upon being released in this manner is readily removed from the chuck. The stopping of the chuck at every 90° allows time for a new ring to feed into the plate opening 29 adjacent the 55 top of the chuck and for the ring that is held by the chuck to be ground by the grinder 13 as well as to permit the ring at the bottom of the chuck to drop out of its opening 29 upon automatic release by the 60 chuck jaw 30.

While the form of the invention herein set forth and described is believed to be the preferred embodiment of the invention, it is nevertheless to be understood that minor

changes may be made therein without departing from the spirit and scope thereof.

What is claimed as new is:—

1. A device of the class described comprising a fixed shaft, a hub journaled thereon, a bracket fixed to the shaft having a head at its free end spaced from the periphery of the hub, an outwardly projecting plate carried by the hub having openings adapted for positioning adjacent said head during the rotation of the hub, and automatic jaws carried by the plate adjacent the openings.

2. A device of the class described comprising a fixed shaft, a hub journaled thereon, a bracket fixed to the shaft having a head at its free end spaced from the periphery of the hub, an outwardly projecting plate carried by the hub having openings adapted for positioning adjacent said head during the rotation of the hub, a radially movable jaw carried by the plate adjacent each of said openings, automatic closing means for the jaws, and means adapted to automatically retract the jaws to open position during the rotation of the hub.

3. A device of the class described comprising a fixed shaft, a hub journaled thereon, a bracket fixed to the shaft having a head at its free end spaced from the periphery of the hub, an outwardly projecting plate carried by the hub having openings adapted for positioning adjacent said head during the rotation of the hub, a radially movable jaw carried by the plate adjacent each of said openings, automatic closing means for the jaws, means adapted to automatically retract the jaws to open position during the rotation of the hub, a magazine positioned adjacent said head at the opposite side of the plate, and operable means within the magazine adapted for the successive discharge of piston rings from the magazine into the openings of the plate and in contact with said head during the operation of the device.

4. An automatic chuck and feed for piston rings comprising in combination with a double disk grinder, an annular plate having ring receiving openings and mounted for turning with said openings between the sides of the grinder, a normally closed clutch jaw for each of said openings, a guide disk for the plate between the sides of the grinder, and automatic retracting means for said jaws adapted for operation subsequently to the grinding operation.

5. An automatic chuck and feed for piston rings comprising in combination with a double disk grinder, an annular plate having ring receiving openings and mounted for turning with said openings between the sides of the grinder, a normally closed clutch jaw for each of said openings, a guide disk

for the plate between the sides of the grinder, a stationary shaft, a cam fixed upon said shaft, hub members secured to said plate journaled upon the shaft with a central 5 chamber within which the cam is positioned, and operative connecting means between said jaws and cam whereby the jaws are adapted for retraction subsequent to each grinding operation and are released for automatic 10 closing at a predetermined point in the rotation of the plate.

6. An automatic chuck and feed for piston rings comprising in combination with a double disk grinder, an annular plate having 15 ring receiving openings and mounted for turning with said openings between the sides of the grinder, a normally closed clutch jaw

for each of said openings, a guide disk for the plate between the sides of the grinder, a stationary shaft, a cam fixed upon said 20 shaft, hub members secured to said plate journaled upon the shaft with a central chamber within which the cam is positioned, operative connecting means between said jaws and cam whereby the jaws are adapted 25 for retraction subsequent to each grinding operation and are released for automatic closing at a predetermined point in the rotation of the plate, and a magazine adjacent the plate adapted for feeding piston rings 30 successively into said openings prior to the closing of said jaws.

In testimony whereof I affix my signature.
JAY HIRAM CUMMINGS.
